UNITED STATES PATENT OFFICE.

HERBERT W. KENWAY, OF NEWTON, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON HEELS.

1,080,150.

Specification of Letters Patent.

Patented Dec. 2, 1913.

Application filed September 25, 1911. Serial No. 651,250.

To all whom it may concern:

Be it known that I, HERBERT W. KENWAY, a citizen of the United States, residing at Newton, in the county of Middlesex and State of Massachusetts, have invented certain Improvements in Machines for Operating on Heels, of which the following description, in connection with the accompanying drawings, is a specification, like reference characters on the drawings indicating like parts in the several figures.

This invention relates to improvements in machines for operating on heels and is herein described as embodied in a heel pricking machine.

An object of the invention is to simplify the construction of pricking machines and improve their operation upon heels which it is desired to attach by nails driven inclined longitudinally of the heel and which accordingly must be pricked obliquely.

Heretofore it has been customary to hold a heel blank between two heel-engaging members the effective faces of which are disposed at an inclination to the path of the awls. It has been found desirable to shape the inclined faces of both the heel holding members to coincide in their inclination with the tread and heel seat surfaces of the heel to be operated upon. The face of the member against which the heel is forced during the working stroke of the awls must be properly shaped to hold the heel against slipping or tilting during this operation or else the awl holes will take a wrong direction, and the face of the die plate through which the awls reciprocate must also be shaped properly to prevent movement of the heel during the stripping or withdrawal of the awls as otherwise the awls will be bent and are likely to be broken or the lifts of the heel pulled apart. Moreover, if a fair bearing is not afforded for both surfaces of the heel when it is subjected to pressure preliminarily to the pricking operation, as is customary, the heel is likely to be distorted. Heretofore the desired shape has been given to the die plate by grinding off on a bevel its effective work-engaging face. By this expedient satisfactory operation is secured in dealing with heels having a given shape but if it is desired to operate upon heels of a different shape, or to vary the inclination of the awl holes in the heel it is necessary to substitute a new die plate having its face

ground to a correspondingly different bevel.

An important feature of the present invention, accordingly, consists in the provision of an auxiliary heel-engaging stop or abutment interposed between the work-engaging face of the die plate and the proximate surface of the heel blank whereby the heel may be held at an inclination to the face of the die plate and the awl passages therein.

Another feature of the invention consists in the provision of a novel form of adjusting means whereby the angle between the face of the die plate and the proximate surface of the heel may be varied and the angle of the awl holes correspondingly regulated. As herein shown, the adjusting means comprises a wedge-shaped member movable relatively to the die plate and supporting the heel engaging stop, the stop being adjusted by the movement of the wedge-shaped member to hold the rear end of the heel at different distances from the plate.

For purposes of illustration the invention will now be described as embodied in a pricking machine substantially of the type disclosed in copending application Serial No. 591,314, filed November 5, 1910, upon an invention of John E. Glidden, although the present invention is not limited to this type of machine but has a more general application.

In the drawings: Figure 1 is a view in side elevation of the operating parts of a pricking machine showing a heel blank in which the awls are inserted, and Fig. 2 is a plan view partially in section on the line 2-2 of Fig. 1 of the part shown in Fig. 1.

As shown in the drawings the machine comprises a head 10 in which is removably received the follower plate 12 having a curved and inclined face shaped to fit the heel seat surface of the heel blank 50 standing upon its breast surface. Oppositely disposed with respect to the follower plate 12 is the perforated die plate 14 having a substantially vertical work-engaging face and horizontal awl passages in which work a gang of awls 16 set in the awl plate 18. The heel blank 50 rests upon a bottom plate 20 which extends outwardly toward the front of the machine affording convenient means for inserting successive blanks in operative position. The heel is positioned laterally by forked yoke 22 adjacent to the face of

the die plate. Means, not shown, are provided for advancing the follower plate 12 to engage the heel blank 50 between itself and the die plate 14, the arrangement being such that, after the heel has been engaged, relative movement of the awls and die plate takes place whereby the awls are forced into the heel blank. The means for advancing the head 10 and causing relative movement of the die plate and awls are not illustrated herein as they form no part of the present invention. They are, however, fully illustrated and described in the co-pending application above identified to which reference may be had for details of construction.

In order to hold the heel blank inclined with respect to the surface of the die plate 14 and the awls 16 the stop 30 is arranged to project from the surface of the die plate 20 adjacent to the rearmost awl and outside the line of the awls where it will engage the tread surface of the heel blank at its rear end. The stop 30 is provided with a flattened head for engaging the heel and a bifurcated shank which is slidably received within a recess in the die plate 14, as shown in Fig. 2. The stop is rigidly supported by the transversely extending bar 32 which passes between the sides of its shank.

30 The supporting bar 32 may be utilized in effecting adjustment of the stop 30 and to this end the rear surface of the stop is made wedge shaped and arranged to contact with a correspondingly inclined surface formed 35 on the bar 32. Any convenient means may be employed to shift the position of the supporting bar. As herein shown a headed adjusting screw 36 is threaded into one end of the bar and fitted with collars on either side 40 of the plate 38 so that one turn of the screw will move the bar through a distance equal to the pitch of the screw thread.

In order to retract the stop 34 there is provided in one face of the bar 32 an inclined slot 35 disposed parallel to the wedge face of the bar and into the slot 35 projects a short retaining stud 37 from the inner surface of one of the bifurcated arms of the stop. It will be seen, therefore, that 45 by movement of the bar toward the right in Fig. 2 the stop is forced outwardly by the action of the wedge face of the bar, while on movement of the bar toward the left the stop is retracted by the action of the inclined slot 35 on the retaining pin 37.

50 In operation a follower plate 12 having the desired shape is fitted into the head 10, a heel blank is placed in position and the stop 30 is adjusted to bear fairly upon the rear end of the heel when the latter rests upon the follower plate. Having made this preliminary adjustment the machine is in readiness to operate uniformly and accurately and without bending of the awls or distortion of the blanks. Should it be de-

sired to vary the inclination of the awl holes in the heel blank a follower plate of different shape may be fitted in the head 10 and a corresponding adjustment made in the position of the stop 30.

70 In the machine of the application above identified the pricking and stripping operations are effected by movement relatively to the awls of the head 10 and die plate 14 with the heel blank held between them but the present invention may be embodied with good advantage in machines in which the heel seat engaging member is stationary and the die plate and awls movable relatively thereto.

80 Having thus described my invention what I claim as new and desire to secure by Letters Patent of the United States is:—

1. A machine for operating on heels having means for adjustably holding heels in 85 positions of different inclinations comprising a plate held against angular movement, a wedge shaped member movable relatively to the plate, a heel engaging device supported by the wedge shaped member and adjust- 90 ed by the movement thereof to tilt the heel about an axis adjacent to its breast edge into different angular positions, and connections for reversely moving the heel engaging device when the wedge shaped member is re- 95 tracted.

2. A machine for operating on heels having, in combination, a die plate provided with awl guiding passages disposed at right angles to its work-engaging surface, a gang 100 of awls operating in said passages, and means disposed out of line with the guiding passages for engaging the tread face of a heel at its curved end and holding it away from the surface of the die plate while the 105 breast end of the tread face bears upon the work-engaging surface of the die plate.

3. A machine for operating on heels having, in combination, a gang of awls, means for supporting a heel blank obliquely with 110 respect to said awls so that the heel may be pricked obliquely, and means for preventing displacement of the heel while the awls are being stripped therefrom including a stop disposed without the rearmost awl and arranged to engage the rear curved end of the 115 tread face of the heel.

4. A machine for operating on heels, having, in combination, relatively movable awls and die plate, and an inclined work support, 120 said die plate having a work-engaging face disposed perpendicularly to said awls, and a stop projecting from said face to maintain the proximate face of the heel at an inclination to said awls, the effective face 125 of the stop being relatively inclined with respect to the work support.

5. A machine for operating on heels, having, in combination, relatively movable awls and die plate, said die plate being arranged 130

- to engage the tread surface of a heel blank near one end, and a member interposed between said die plate and heel and located out of line with the awls for holding the 5 other end of said tread surface away from the surface of the die plate.
6. A machine for operating on heels, having, in combination, relatively movable awls and heel seat plate, said plate having its 10 work-engaging face oblique to the path of relative movement, an interposed die plate having its face toward said heel seat plate perpendicular to the path of relative movement of the awls and heel seat plate, and a 15 heel engaging device projecting from said surface of the die plate, having a work engaging face of less area than the face of the heel and serving to hold a heel blank in engagement with said oblique heel seat plate 20 without displacement during the operation of stripping the awls.
7. A machine for operating on heels, having, in combination relatively movable awls and die plate, said die plate having a work 25 engaging face and a work engaging stop projecting from said face, the stop being supported within the face of said die plate, and having its effective surface disposed substantially parallel to the face of the die 30 plate.
8. A machine for operating on heels, having, in combination relatively movable awls and die plate, and a work support inclined with respect to the path of the awls, said die 35 plate having a work engaging face and an adjustable work engaging stop projecting therefrom, and having its effective surface inclined with respect to the work support.
9. A machine for operating on heels, having, in combination relatively movable awls and die plate, said die plate having a work 40 engaging face, a stop associated with the die
- plate and having a work engaging portion and a wedge shaped surface and an adjustable wedge member for supporting said stop. 45
10. A machine for operating on heels, having, in combination relatively movable tools and die plate, said die plate having tool guiding passages therein, a work engaging stop mounted in said die plate, and means 50 for positively adjusting said stop relatively to the die plate in the direction of the tool guiding passages, whereby the work may be sustained in different positions relatively to the path of said tools. 55
11. A machine for operating on heels having means for adjustably holding heels in positions of different inclinations comprising a plate, a wedge-shaped member arranged for adjusting movement in a path 60 substantially parallel to the surface of the plate and in a direction longitudinally of the heel, and a heel engaging device supported by the wedge-shaped member and adjusted by the movement thereof to hold the rear 65 end of the heel at different distances from the plate.
12. A machine for pricking heels having a vertically disposed die plate, a follower movable horizontally to engage a heel presented breast down to the machine and press it against the die plate, and an adjustable stop for engaging the rear end of the heel and tipping it away from the die plate at one end, the heel bearing obliquely at its 75 other end on the die plate.

In testimony whereof I have signed my name to this specification in the presence of two subscribing witnesses.
